UNITED STATES PATENT OFFICE

JOHN B. DYER, OF ANDERSON, INDIANA, ASSIGNOR TO DELCO-REMY CORPORATION, OF ANDERSON, INDIANA, A CORPORATION OF DELAWARE

ENGINE STARTING DEVICE

Application filed July 3, 1929. Serial No. 375,845.

This invention relates to apparatus for starting an internal combustion engine, and particularly to the type of apparatus which comprises an electric motor and means for connecting the motor with the gear of an engine to be started, and including a pinion and provisions whereby the pinion will automatically be demeshed from the engine gear when the engine starts and provisions whereby said pinion will be locked in the demeshed position during the self-operation of the engine. An example of an engine starter of this type is disclosed in the co-pending application of John B. Dyer, Serial No. 354,734, filed April 13, 1929, which comprises a pinion adapted to be shifted manually into engagement with an engine gear for engine starting purposes, said pinion being shifted automatically out of engagement with said engine gear when the engine becomes self operative.

One of the objects of the present invention is to provide an engine starter with a pinion adapted to be moved manually into engagement with the engine gear for engine starting purposes, said pinion being locked in the demeshed position so that it cannot be moved into engagement with the engine gear while the engine is self operative.

Further objects and advantages of the present invention will be apparent from the following description, reference being had to the accompanying drawings, wherein a preferred form of the embodiment of the present invention is clearly shown.

In the drawings:

Fig. 1 is a fragmentary view, partly in longitudinal section, of an engine starting apparatus embodying the present invention.

Fig. 2 is a sectional view on the line 2—2 of Fig. 1, certain electrical elements adapted to cooperate with the actual starting motor being shown diagrammatically in this view.

Fig. 3 is a longitudinal, sectional view of a portion of the apparatus, this section being taken along the line 3—3 of Fig. 4.

Fig. 4 is a sectional view taken along the line 4—4 of Fig. 1.

Referring to the drawings, the numeral 20 designates the field frame of an electric

motor which is secured to a gear housing 21, said gear housing being adapted to be attached to the frame of the engine, not shown. The field frame 20 provides a bearing, which is not shown, for supporting the left end of a motor armature shaft 22, the right end of said shaft being supported in a bearing 23 provided in the gear housing 21.

The operation of the electric motor, or more specifically the circuit of the electric motor is controlled by a switch having a casing 24, a fragment of which is shown in the Fig. 1. Contacts are enclosed within the casing, one of said contacts being supported by the plunger 25 which is normally held in contact open position by the spring 26.

The means for connecting the shaft 22 with the fly-wheel 30 of the engine to be started comprises a pinion 31 and apparatus for automatically causing the pinion to be demeshed from the gear 30 when the engine starts. Automatic demeshment of the gear results from employing helical splines 32 on the shaft 22. Upon the helical splined portion of the shaft 22 there is mounted a pinion shifter 37 which, when moved longitudinally of the shaft 22, will rotate relative to said shaft. A tubular extension 35, secured to the pinion in any suitable manner, has longitudinal grooves 36 which are engaged by tangs on the pinion shifter 37. A spring 38 is contained within the tubular extension 35, one end of said spring engaging the pinion 31, the other end of said spring engaging the pinion shifter 37 and normally holding said pinion shifter in spaced relation with the pinion.

From the foregoing it may be seen that motion of the pinion shifter 37 axially of the shaft toward the gear 30 will cause the pinion 31 to be yieldingly urged toward the gear 30, and, in case of gear tooth abutment, pinion 31 will yieldingly be pressed by the spring 38 against the gear 30 while the shifter 37 continues to move axially of the shaft in order to rotate the pinion into meshing registration with the gear. It is desirable that the pinion be yieldingly pressed against the engine gear while being rotated, for the reason that a yielding pressure will permit the pin-

ion to recede along the shaft slightly while being rotated in engagement with the end face of the gear tooth. If the pinion were not permitted to recede slightly it might become interlocked with the engine gear due to the engagement of the substantially roughened surfaces at the ends of the abutting pinion and gear teeth.

The manually operable means for actuating the pinion shifter 37 includes a lever 40 adapted to be operated by a pedal 40a. The lever 40 is pivotally supported upon a stud 41 secured to the motor housing by the nut 42 as shown in the Fig. 2. Lever 40 is maintained in normal position as shown in Fig. 1 by a spring having its intermediate portion 43 coiled about the stud 41, the end portions 44 and 45 engaging respectively the housing 21 and the lever 40 as shown in the Fig. 1. The spring 43 is so biased as to urge lever 40 in a counterclockwise direction. A stud 46 is supported upon the lever so that it is adapted to engage the switch plunger 25 when the lever 40 has been operated a predetermined distance in a counterclockwise direction. The lever has a stud 50 attached adjacent the lower end thereof, said stud being normally received by a notch 51 provided in a sleeve 52 which is mounted concentrically upon a hub 53. Hub 53 is supported by the shaft 22, discs 54 and 55 being provided on the hub 53 whereby the sleeve 52 is properly supported on said hub. A spring 70 surrounding the hub 53 is interposed between the pinion shifter 37 and the disc 55, said spring 70 normally spacing the sleeve assembly 52 from the shifter 37. The sleeve 52 has an edge surface 66 so constructed and arranged that it is adapted to move the sleeve 52 toward its normal position when the engine becomes self-operative. An opening 100 is provided in the sleeve 52. Substantially in alignment with the opening 100 when the sleeve 52 is in its normal pinion demeshing position, there is a recess 101 provided in the gear casing 21. The numeral 102 designates the cup-shaped housing of the electro-magnet 103, said housing having an extending portion 104 which screw-threadedly engages the outer end of the recess 101. Within the housing 102 an electromagnetic winding 105 is provided, said winding surrounding a hollow core 106 which slidably supports a plunger armature 107. An end cover 108 is provided for the housing 102. A spring 109 in the recess 101 engages an annular flange 110 upon the stem of the plunger armature 107 yieldably urging the plunger armature toward the right as regards Fig. 2 so that the end thereof is normally in engagement with the end cover 108. The inner end of the plunger armature 107 extends through an opening in the gear casing 21 into the interior thereof, said plunger armature being in coaxial alignment with the opening 100 in the

sleeve 52 when said sleeve 52 is in the normal, pinion demeshing position. One side of the electromagnet winding 105 is grounded, the other end of said winding being electrically connected with the dynamo 115 which is connected with the engine and driven thereby in any suitable manner.

The pedal 40a is carried on a shaft 120 which may be the shaft adapted to control the clutch of the motor car upon which the present device is used. Upon shaft 120 a lever 121 is rotatably supported, said lever having an abutment 122 which is adapted to be engaged by the abutment 123 provided on the pedal 40a after the pedal has been moved through a predetermined portion of its range of movement. From this it may be seen that the pedal 40a, which may be the clutch control pedal, is adapted to cooperate with the lever 121, connected with the motor lever 40 by a rod 128, that the pedal 40a may be moved or operated to control the clutch throughout a portion of its range without in any way engaging the lever 121 to affect the starting motor. Also, if it is desired to start the engine, pedal 40a is moved through a sufficient range to entirely disconnect the clutch before the movement of said pedal causes any movement of the starting pedal mechanism, so that when the starting motor is being operated by the pedal 40a the clutch will be entirely disconnected.

When it is desired to start the engine, pedal 40a is depressed so that the abutment 123 thereof will engage the abutment 122 of lever 121 causing said lever to be moved counterclockwise and through the rod 23 exert a counterclockwise movement to the motor lever 40. As the lever 40 moves counterclockwise, the stud 50 will engage the one side of the slot 51, causing the sleeve 52 to be moved toward the right as regards Fig. 1, the spring 70 exerting pressure upon the pinion shifter 37 and said pinion shifter 37 through the spring 38 exerting a pressure toward the right upon the pinion 31. If the teeth of the pinion 31 engage properly with the gear 30 of the engine, the movement of the lever 40 counterclockwise will at a predetermined point depress the switch plunger 25 to close the contacts of the electric motor circuit, causing the electric motor to rotate whereby the pinion 31 will rotate the engine gear 30 and consequently the engine for starting purposes.

At this time it may be mentioned that while the engine is inoperative, the dynamo 115 will be inoperative and consequently the electromagnet 103 will not be energized. This permits spring 109 to move the plunger armature 107 toward the right as regards Fig. 2 so that the inner end thereof will not extend into the opening 100 of the sleeve 52, consequently sleeve 52 is free to move toward the right as regards Fig. 1 to shift the pin-

ion shifter 37 for pinion enmeshment while the engine is inoperative.

As is clearly described in the copending application of John B. Dyer mentioned heretofore, automatic demeshment of the pinion takes place when the engine has become self-operative. Rotation of the pinion 31 by the gear 30 will throw the starting mechanism back into its normal position as shown in the Fig. 1, thus sleeve 52 will be moved so that its opening 100 will align with the plunger armature 107 of the electromagnet 103. Self-operation of the engine causes the dynamo 150 to operate and thus energize the electromagnet 103 whereby the plunger armature 107 will be moved to the left as regards Fig. 2 against the effect of spring 109 and thus the other end of said plunger armature will enter into the opening 100 in the sleeve 52 and consequently will lock said sleeve 52 against axial movement relative to the shaft 22. Thus while the engine is operating, a complete movement of the pedal 40a counterclockwise throughout its entire range of movement will be prevented substantially, due to the fact that the plunger 107 extends into the opening 100 of the sleeve 52 thus locking it against longitudinal movement relative to the shaft 22 and thereby the slot 51 of said sleeve 52 forms a stop which is engaged by the stud 50 of the lever 40, preventing counterclockwise movement of the lever 40 while the engine is self-operative. The spacing between the abutments 122 of lever 121 and 123 of pedal 40a permits movement of the pedal 40a sufficiently to operate the shaft 120 to control the clutch action, and thus the lock provided by the plunger armature 107 does not in any way affect the operation of the pedal 40a to operate the engine clutch.

The present invention embodies essential features of the invention disclosed in the aforementioned application of John B. Dyer, in that the meshing of the pinion with the engine gear is accomplished by manual effort before the motor switch is closed, thereby minimizing chances of damage to the gear teeth, and in that the pinion is demeshed automatically regardless of the status of the operating lever, thereby dispensing with the use of an over-running clutch between the pinion and motor shaft. The present invention constitutes an improvement over the copending application Serial No. 354,734 of John B. Dyer in that it provides locking means automatically operable and under control of engine operation for locking the electric motor against manual shifting for engine starting purposes while the engine is self-operative, thus a clashing of gears and possible damage is substantially eliminated.

While the form of embodiment of the present invention as herein disclosed, constitutes a preferred form, it is to be understood that other forms might be adopted, all coming

within the scope of the claims which follow.

What is claimed is as follows:

1. Engine starting apparatus comprising in combination, a pinion movable into mesh with the gear of an engine to be started; manually operable means adapted to move the pinion into enmeshment with the gear; a latch adapted to be moved out of its normal position to engage the manually operable means for retaining it in inoperative position; and an electromagnet for moving and retaining said latch out of its normal position while the engine is self-operating.

2. Engine starting apparatus comprising in combination, a pinion movable into mesh with the gear of an engine to be started; means for automatically demeshing the pinion from the engine gear when the engine starts; manually operable means for moving the pinion into mesh with the engine gear and comprising an actuator, a member adapted to transmit motion from the actuator to the pinion said member having an opening; and engine controlled means adapted to extend into the opening of said member to maintain said member in pinion demeshing position during the operation of the engine.

3. Engine starting apparatus comprising in combination, a pinion movable into mesh with the gear of an engine to be started; means for automatically demeshing the pinion from the engine gear when the engine starts; manually operable means for moving the pinion into mesh with the engine gear and comprising an actuator, a member adapted to transmit motion from the actuator to the pinion said member having an opening; and electrically controlled apparatus adapted to extend into the opening of said member to maintain said member in pinion demeshing position during the self-operation of the engine.

4. Engine starting apparatus comprising in combination, a pinion movable into mesh with the gear of an engine to be started; means for automatically demeshing the pinion from the engine gear when the engine starts; manually operable means for moving the pinion into mesh with the engine gear and comprising an actuator, a member adapted to transmit motion from the actuator to the pinion said member having an opening; a latch adapted to be moved into the opening of said member when said member is in the pinion demeshing position; and an electromagnet for moving and retaining said latch out of its normal position and into engagement with the opening of said member while the engine is self-operating.

5. Engine starting apparatus comprising in combination, an electric motor having a housing; a shaft in said housing; a pinion shiftably supported upon and driven by said shaft; manually operable means supported by the housing for shifting the pinion into

enmeshment with the gear of the engine for starting purposes; and an electromagnet supported by the housing, said electromagnet having a plunger adapted to be moved into engagement with the pinion shifting means to maintain it in normal, pinion demeshing position when said electromagnet is energized.

6. Engine starting apparatus comprising, in combination, an electric motor having a housing; a shaft in said housing; a pinion shiftably supported upon and driven by said shaft; manually operable means supported by the housing for shifting the pinion into enmeshment with the gear of the engine for starting purposes; a dynamo driven by the engine; an electromagnet supported by the motor housing and adapted to be energized by the dynamo; and a magnet plunger in the electromagnet, yieldably urged out of engagement with the pinion shifting means, but adapted to engage said means and lock it in pinion demeshing position while the dynamo is energizing the electromagnet during the operation of the engine.

7. Engine starting apparatus comprising, in combination, a dynamo driven by the engine; a starting motor having a housing and an armature shaft journalled therein; a pinion rotatable with but slidably supported on said shaft; a sleeve surrounding the shaft and operatively connected with the pinion for moving said pinion longitudinally of the shaft and into enmeshment with the gear of the engine to be started; manually operable means for moving the sleeve to shift the pinion toward the engine gear; and means for locking said sleeve against movement during the operation of the engine.

8. Engine starting apparatus comprising, in combination, a dynamo driven by the engine; a starting motor having a housing and an armature shaft journalled therein; a pinion rotatable with but slidably supported on said shaft; a sleeve surrounding the shaft and operatively connected with the pinion for moving said pinion longitudinally of the shaft and into enmeshment with the gear of the engine to be started; manually operable means for moving the sleeve to shift the pinion toward the engine gear; and electromagnetic means automatically responsive to the operation of the dynamo for engaging the sleeve to maintain it inoperative during the operation of the engine.

9. Engine starting apparatus comprising, in combination, a dynamo driven by the engine; a starting motor having a housing and an armature shaft journalled therein; a pinion rotatable with but slidably supported on said shaft; a sleeve surrounding the shaft and operatively connected with the pinion for moving said pinion longitudinally of the shaft and into enmeshment with the gear of the engine to be started; manually operable

means for moving the sleeve to shift the pinion toward the engine gear; a plunger adapted to be moved out of its normal position into engagement with the sleeve to lock said sleeve against movement; and an electromagnet automatically responsive to the operation of the dynamo for moving the plunger out of its normal position to engage the sleeve.

In testimony whereof I hereto affix my signature.

JOHN B. DYER.
